DESIGN FOR A DOLL

Blanche Squier and Bernice Squier,
Battle Creek, Mich.

Application March 23, 1948, Serial No. 145,288

Term of patent 7 years

(Cl. D34—4)

To all whom it may concern:

Be it known that we, Blanche Squier and Bernice Squier, citizens of the United States, residing at Battle Creek, in the county of Calhoun and State of Michigan, have invented a new, original, and ornamental Design for Dolls, of which the following is a specification, reference being had to the accompanying drawing, forming part thereof.

We claim:

The ornamental design for a doll, as shown.

BLANCHE SQUIER.
